(57) **CLAIM**

The ornamental design for an apparatus for wireless communication, as shown and described.

DESCRIPTION

FIG. 1 is a top perspective view of an apparatus for wireless communication;

FIG. 2 is a top view thereof;

FIG. 3 is a right side view thereof; and,

FIG. 4 is a left side view thereof.

The broken lines shown in the drawings that are immediately adjacent to the shaded areas (and which define unshaded regions) represent the bounds of the claim, while the broken lines within the boundaries are directed to environment. The broken lines and the unshaded regions form no part of the claimed design. The areas which lie directly underneath of areas shown in broken lines in the drawings are claimed.
